UNITED STATES PATENT OFFICE.

BENJAMIN MIFFLIN HOOD, OF ATLANTA, GEORGIA.

MACHINE FOR FORMING CLAY TOWER-SPIRALS.

1,346,786.

Specification of Letters Patent. Patented July 13, 1920.

Application filed November 2, 1918. Serial No. 260,834.

To all whom it may concern:

Be it known that I, BENJAMIN MIFFLIN Hood, a citizen of the United States, and resident of Atlanta, Georgia, have invented 5 certain new and useful Improvements in Machines for Forming Clay Tower-Spirals, of which the following is a specification.

This invention relates to improvement in a machine for forming clay tower spirals, 10 and it consists in a novel arrangement and construction of parts, the detail of construction will be hereinafter fully described and set forth in the claims.

The object of my invention is to construct a machine in which is placed a quantity of plastic clay, said clay by means of the mechanism being hollowed, intermingled and mixed, and advanced forward into dies, which dies are equipped with a rotating 20 spiral which forms on the interior of a clay spiral an integral spiral wall. This product after being formed by the machine is then baked and vitrified and is used in connection with acid making.

25 A further object of my invention is to construct a machine which will simultaneously mix a plastic clay and advance it forward by a determined speed as well as operating in spiral forming mechanism at a speed independent of the remaining mechanism.

Figure 1, is a top plan view of my complete machine.

Fig. 2, is a side view of the same.

35 Fig. 3, is a detail elevation.

Fig. 4, is a front elevation.

Fig. 5, is a top plan view with parts broken away and in section.

Fig. 6, is a detail view showing the hollow shaft made use of in connection with my machine.

Fig. 7, is a detail front view of the spiral forming die.

Fig. 8, is a horizontal sectional view of the same.

Fig. 9, is a detail view with portions of the hollow shaft, together with the spiral and conveyer for advancing the clay.

In the construction of my machine I provide a suitable base 10 on which is mounted a standard or frame 11. On the upper portion of which is supported the conveyer housing 12, a portion of which terminates into a hopper 13 in which the plastic clay 55 is fed.

On the base 10 is also mounted standards

14, which are provided with journal bearings in which are supported a pair of shafts 15 which run horizontally with the machine and are likewise supported in journal bearings 16, located in close proximity with a conveyer housing, and said shafts extending into the housing in a manner as that shown. The pair of shafts 15 are of hollow construction, the shaft 17 of the pair is 60 provided with a large gear wheel 18, a small gear wheel 19 and a gear pinion 20. This gear pinion 20 is arranged in mesh with a gear pinion 21, formed on the hollow shaft 22, which is one of the pair. 70

Within the hollow shaft 17 is supported a second hollow shaft 23, its rear end being provided with a large gear wheel 24, said wheel being arranged in mesh with a small gear wheel 25, which is mounted on the 75 drive shaft 26, having bearing in journals 27 and 28 formed on the standards. Within the hollow shaft 22, is a second hollow shaft 29, on the rear end of this shaft is a gear pinion 30 which is arranged in mesh with 80 the gear wheel 19 supported on the shaft 17.

On the drive shaft 26 is located a drive pulley 31, which is controlled by a clutch mechanism 32, and the end of the shaft 26 is supported in the journal 33 supported 85 on the standard 34.

On the hollow shafts 17 and 22 and located within the conveyer housings are located a plurality of sleeves 35, each of which is provided with a wing 36; these wings are 90 arranged at such a length and angle and the sleeves are set in locked position on the shaft so that the wings are staggered so that the clay within the compartment is properly agitated during the rotation of the shafts, 95 and at the same time advancing the clay forwardly within the housing.

In the front part 37 of the housing I place upon the shaft similar sleeves 38, which are provided with spiral wings 39 which have a 100 tendency to grip the clay and advance it forward toward the die casing 40.

Within the forward ends of the inner hollow shafts are inserted and fixed a shank 41 to the forward end of which is attached the spiral 42 which when in rotation forms a spiral wall within the product, as the same passes out through the die cylinder 43 supported in the die casing.

The shaft 41 is provided with a flange 44 110 which is of such size as to fit within the sleeve 38 of one of the conveyer members

and buts up tightly against a washer 45 which acts as a seal or preventative from the plastic clay forcing its way into the hollow shafts.

5 The inner hollow shafts are provided with an aperture 46, which permits oil or grease inserted into the inner hollow shafts to contact with the inner surface of the outer hollow shafts thereby properly lubricating the 10 same during the rotation.

The machine in general is properly braced by the rod 47 connected to the arms 48 and 49; this is for the purpose of properly bracing the machine on account of the excessive 15 pressure required for properly handling the plastic clay.

The clutch mechanism which controls the pulley wheel 31 is manipulated by the hand lever 50 connected to the rod 51, which in 20 turn is connected to the lever 52 which has connection with the clutch apparatus and is pivoted at its upper end to the supporting arm 53.

I will not go into the detail description 25 of the die mechanism and spiral as this particular structure is the invention of John Walter Thomas, who is simultaneously filing an application for patent on this structure and who is in business relations with me 30 in the manufacture of the clay tower spiral product.

The essential feature of my invention and the difference in construction between it and the Mueller patent is the arrangement of 35 the hollow shafts, one operating within the other and at different speeds, the clay being advanced under pressure at one speed while the spiral is operated at a greater speed so as to properly form the spiral wall of the 40 product while the clay cylinder is passed out through the die cylinder.

The operation of my invention is as follows:

As rotation is imparted to the pulley wheel 45 31, and by the manipulation of the clutch the machine is then placed in operation; the heavy gear pinion 54 which is mounted on the shaft 26 and meshing with the large gear 18 will rotate the shaft 17, likewise the 50 gear pinion 20 which meshes with the gear pinion 21 rotates the shaft 22 in opposite direction. This movement then rotates the conveyer and mixing wings in opposite directions handling and advancing the plastic 55 clay by the rotation of the shaft 17; the gear wheel 19 is likewise rotated imparting mo-

tion to the pinion 30 which is mounted on the inner hollow shaft 29 of the hollow shaft 22; and motion is imparted to the hollow shaft 23 by the gear wheel 24 which meshes 60 with the gear wheel 25 mounted on the shaft 26, the size of these gears being such as to place the inner hollow shafts in rotation at a speed somewhat greater than the speed of the outer hollow shafts, and by the 65 rotation of the two inner hollow shafts the spirals connected thereto are rotated in opposite directions at the speed to properly conform with the movement of the plastic clay through the dies.

Having fully described my invention what I claim is:

1. A machine for making clay tower spirals, comprising a hopper in which is placed plastic clay, conveyers located therein for 75 advancing the clay, a hollow shaft, a second hollow shaft operating within the first hollow shaft for controlling the movement of the clay and operating a spiral for producing a cylindrical clay body with an interior spiral wall, the inner hollow shaft acting as an oiling device, substantially as specified.

2. A machine of the character described comprising a pair of hollow shafts mounted 85 in bearings, gears mounted on the same, a second hollow shaft and filled with oil mounted within each of the first mentioned hollow shafts, gears connected to the same and controlled thereby, a spiral rotated by 90 the inner hollow shafts and operating at a speed in variance with the speed of the outer shafts, substantially as specified.

3. A machine of the character described comprising a pair of hollow shafts mounted 95 in bearings, a conveyer housing through which the same extends, conveyers mounted on the shafts and within the housing, a second hollow shaft mounted within the first hollow shaft and filled with oil, spirals connected thereon and operating at the end of the conveyer housing, a plurality of gears mounted on the inner and outer hollow shafts for rotating the same at different speeds, substantially as specified.

In testimony whereof I have signed my name to this specification, in presence of two subscribing witnesses.

BENJAMIN MIFFLIN HOOD.
